UNITED STATES PATENT OFFICE

CHARLES S. PRICE, OF BETHLEHEM, PENNSYLVANIA, ASSIGNOR TO L. F. GRAMMES & SONS, INC., A CORPORATION OF MARYLAND

NAILING MACHINE

Application filed September 9, 1926. Serial No. 134,440.

My invention relates to nailing machines in general and especially to machines of that character adapted for use in the manufacture of boxes, such as cigar boxes, and the like.

5 One object of the invention is to provide a nailing machine in which the shocks or parts of a box are assembled and supported in nailing position and automatically nailed, in each 10 operation of the machine, the mechanism being under the convenient control of the operator and being so arranged that the operation of the machine may be repeated in rapid succession, whereby the machine will have a high 15 output and the desired boxes may be easily and cheaply manufactured.

Another object of the invention is to provide a nailing machine in which a single treadle controls both the feeding of parts of the box to be nailed, and the operation of the 20 nailing mechanism, the arrangement being such that the nailing operation occurs after the feeding operation, but with such a short 25 interval that they are practically simultaneous. This is an important feature since the quicker these two operations follow each other, while maintaining their proper sequence, the more rapidly can the operator turn out boxes with the machine.

20 A further object of the invention is to provide means for assembling and supporting all of the parts of the box, without a cover, in inverted position with the bottom extending over the sides and ends, and the parts all unattached to each other, and means for automatically 30 nailing the bottom to each of the sides and ends so as preliminarily to secure the parts together in assembled position and enable the box to be handled as a unit until 35 and during the subsequent fastening together of the sides and ends at the corners of the box in any desired manner and by any suitable means.

40 A further object of the invention is to provide means for yieldingly supporting the bottom of the box in inverted position so as to afford clearance to permit other parts of the box to be assembled and supported beneath, and in spaced relation to, the bottom, the 45 yielding supporting means also permitting

the bottom of the box to be depressed into contact with and nailed to such other parts in the nailing operation and serving thereafter to apply a stripping force.

55 A further object of the invention is to provide a box form which is moved into and out of operative relation to the nailing mechanism, and is adapted in inoperative position conveniently and quickly to be loaded with certain of the box parts, together with means 60 for automatically assembling the remaining parts of the box on the form after it is moved into operative position, the box, when nailed, being withdrawn from the nailing mechanism by and upon the return movement of the form. 65

70 A further object of the invention is to provide mechanism for feeding parts of the box to assembled position substantially simultaneously, and yet in sufficient sequence to cause one to overlap another to form a butt joint 75 at a corner of the box.

75 A further object of the invention is to provide means for supporting the nailing mechanism, and the driving mechanism therefor, so that the same may be handled as a unit and readily applied to and removed from the main frame of the machine and also conveniently shifted bodily therein toward and away from the work table and held at the desired elevation above the latter to suit 80 the height of box to be operated upon. By this means the capacity of the machine may be varied independently of the work table which may thus be maintained at the height found most comfortable and convenient for 85 the operator and most conducive to efficient results.

90 A still further object of the invention is to provide a nailing machine which is adapted to nail simultaneously along all four edges of a box or other work, which may be conveniently adjusted for boxes of different dimensions, which is reliable and efficient in operation, and which may be readily assembled or disassembled as occasion requires. 95

100 With these and other objects in view the invention comprises all of the various novel features of construction and arrangement hereinafter set forth.

Referring to the accompanying drawings:—

Figure 1 is a side elevation of my improved nailing machine, showing the treadle fully depressed and the various parts in the positions which they occupy when the nails are being driven.

Figure 2 is a horizontal section showing the work table and the parts mounted thereon in top plan view, the treadle and clutch rod mounted below the work table being omitted for the sake of clearness.

Figure 3 is an enlarged detailed view, partly in longitudinal section and partly in elevation, showing the jaw in the fully gripping position which it occupies when the treadle is fully raised and the machine is at rest, the box form being in its inoperative position in which it is partly loaded manually with one side and the bottom of the box.

Figure 4 is a similar view showing the box form moved into its operative position, and the jaw raised, through the initial downward movement of the treadle, to partly gripping and partly releasing position.

Figure 5 is a similar view showing the jaw raised to fully releasing position on the further downward movement of the treadle.

Figure 6 is a fragmentary longitudinal sectional view, partly in elevation, illustrating the relation between the parts when the form is moved into operative position and before the operation of the jaw.

Figure 7 is a similar view, in transverse section, showing the parts in the same relative positions.

Figure 8 is a fragmentary longitudinal sectional view, partly in elevation, showing the relation of the parts when the jaw is in fully releasing position.

Figure 9 is a similar view, in transverse section, illustrating the parts in the same relative positions.

Figure 10 is an enlarged fragmentary side elevation, partly in section, showing the nailed box on the form and partly stripped therefrom ready for withdrawal from under the nailing mechanism.

Figure 11 is an enlarged fragmentary perspective view showing the form in its inoperative position with a side and the bottom of the box assembled thereon and located by and between the guages on the work table.

Figure 12 is a top plan view of such parts, partly broken away.

Figure 13 is a fragmentary front elevation, partly in section, of the same parts.

Figure 14 is a fragmentary plan view similar to Figure 12, but showing the form carrying the nailed box and withdrawn to a position in which the box may be removed.

Figure 15 is an enlarged fragmentary perspective view showing the relation between the form and the magazines when the form

is in its operative position, the box parts being omitted for the sake of clearness.

Figure 16 is an enlarged perspective view of a box produced by my invention, after being stripped from the form and turned right side up.

Figure 17 is a top plan view showing the overhead driving mechanism, certain parts being omitted for the sake of clearness.

Figure 18 is a fragmentary view in front elevation showing the carrier frame (without the nailing and driving mechanisms which it supports), adjustably mounted in the main frame of the machine.

Figure 19 is a fragmentary transverse section through the hammer and chuck frames, the section being taken on lines 19—19 of Figures 22 and 24.

Figure 20 is a detail perspective view of the front side of the hammer frame.

Figure 21 is an enlarged detail perspective view of one of the chuck brackets.

Figure 22 is a top plan view of the chuck frame.

Figure 23 is a front elevation thereof.

Figure 24 is a top plan view of the hammer frame.

Figure 25 is a front elevation thereof.

Figure 26 is a fragmentary diagrammatic view of the clutch controlling mechanism.

Figures 27 and 28 are fragmentary detail views of parts thereof.

Figure 29 is a detail view showing the key locking a sleeve on a standard of the main frame.

Figure 30 is a detail view showing a chuck lowered adjacent the work and its hammer projecting therefrom in driving a nail, and

Figure 31 is a detail view showing a modified form of mounting for the finger opposite the front face of the form.

Similar reference numerals indicate similar parts throughout the various views.

My nailing machine comprises, in general, a suitable frame, a work table, means for assembling and supporting the box parts on the work table in position to be nailed, nailing mechanism, driving mechanism therefor, and means under control of the operator for controlling both the assembling means and the driving mechanism.

The main frame 1 preferably consists of a pair of transversely spaced standards 2, which are in the form of round bars and are supported in upright position by a stand or pedestal 3. These standards project upwardly from the stand with the space between their upper portions free and unobstructed except as hereinafter pointed out. Each standard is mounted in a pair of vertically spaced, aligned socket members 4 which extend forwardly from the body of the stand and support the lower portion of the standard in spaced relation thereto.

The work table 5 is mounted on the lower

portions of the standards and comprises a pair of brackets 6 projecting forwardly therefrom and supporting the table top 7. At their rear ends these brackets are formed with sleeves 8 which slide on the respective standards 2 between the upper and lower socket members 4. The sleeves are preferably offset below the table top 7 so as to accommodate the upper socket members 4 when the table is moved to its uppermost position.

In order to adjust the table vertically on the standards I provide a transverse shaft 9 journaled in, and extending between, ears 10 projecting rearwardly from the respective sleeves. Pinions 11 are mounted on the shaft at its opposite ends and project through slots 12 in the sleeves 8, into meshing engagement with racks 13 provided on the standards. There is a crank 14 on one end of the shaft 23 by means of which the pinions may be rotated in one direction or the other to raise or lower the sleeves 8 to shift the work table 5 to the height found most convenient and comfortable to the operator, and suitable for maximum efficiency. A pawl 15 is pivoted on one of the ears 10 and engages a ratchet 16 on the shaft 9 to retain the table at the desired elevation. However, the table may be more securely fixed in adjusted position by means of keys 17 arranged in grooves or key-ways 18 in the inner surfaces of the sleeves 8 and extending longitudinally throughout the length thereof, as shown in Figure 29. Set screws 19 are threaded into the sleeves and impinge against the keys 17 to force the same into binding engagement with the standards. The inner ends of the set screws are preferably reduced and project into sockets 20 in the keys to hold the same assembled in the sleeves and against longitudinal displacement therefrom when the set screws are backed off to release the keys from the standards.

The table top 7 is preferably, although not necessarily, cruciform in plan view, as shown in Figure 2, and is extended forwardly, laterally, and rearwardly, beyond the brackets 6, as indicated at 21, 22 and 23 respectively, the rear extension 23 extending between the standards 2 and beyond the body portion of the stand 3. These extensions may be formed separately from the central portion of the table top and suitably secured thereto as by depending flanges 24 abutting against each other with bolts or other fastening devices 25 passing therethrough. In order to further support and strengthen this overhanging structure the lateral extensions 22 and the rearward extension 23 are each provided at their outer end with a leg 26 adapted to rest on the floor and preferably formed of telescoping sections secured together, as by a set screw 27, in suitably adjusted position according to the elevation of the work table in the main frame 1.

The means for assembling the shooks or

box parts include a box form 28 having a body 29 which conforms in horizontal section to the size and contour of the inside of the box which it is desired to manufacture and which is preferably arranged, where an oblong box is to be made, with its longer dimension extending transversely of the machine. Superposed upon the body is a platform 30 which is suitably mounted for independent vertical movement with respect thereto. In the present instance the platform is secured to the upper ends of a plurality of vertically disposed guide rods 31 sliding in openings 32 in the body 29. The openings are counterbored at each end to provide upwardly and downwardly facing shoulders 33 and 34. A coiled expansion spring 35 encircles the upper end of each of the guide rods and is seated in the upper counterbored portion of the corresponding opening 32 and interposed between the upwardly facing shoulder 33 thereof and the platform 30, so as to yieldingly support the latter in spaced relation to the body 29. Stops 36 are provided on the lower ends of the guide rods within the lower counterbored portions of the openings 32 and are adapted to abut against the downwardly facing shoulders 34 to limit the upward movement of the platform under the influence of the springs and to prevent the guide rods from being withdrawn from the body of the form.

The body 29 preferably rests upon, and is suitably secured to, a plate or bed 37 which is in contact with the upper surface of the work table. The bed is flush with the end faces of the body of the form, but is preferably of a size to project slightly beyond the front and rear faces of the body to provide upwardly facing shoulders 38 and 39 respectively, which extend along these faces and are of a width equal to the thickness of the boards from which the box is to be constructed. These shoulders are raised slightly above the surface of the work table for a purpose to be hereinafter set forth.

The box form 28 is mounted to move longitudinally of the machine (that is, forwardly and rearwardly) in a predetermined path over the central portion and forward extension of the table top. This may be accomplished in any suitable manner. As one means for effecting this mounting I have provided the bed 37 of the form with a depending fin 40, which operates in, and is guided by, a longitudinal slot 41 formed in the table top. With this arrangement the form may be readily removed from the machine by merely lifting it to withdraw the fin from the slot, and this makes it possible conveniently to substitute, when desired, another form of a different size or contour.

The fin projects forwardly beyond the bed 37 of the form and carries a finger 42 which preferably bears against the front edge of the

bed and projects upwardly above the shoulder 38 in substantially parallel relation to the front face of the body 29 and to a height above the plane of the upper surface of the platform 30 when the latter is in its normal or raised position, the upper extremity of the finger being preferably out-turned and inclined forwardly and upwardly as indicated at 42¹. This finger is preferably constructed 10 of a strip of spring material bent at right angles at its lower end to provide a base 43 which is secured to the forwardly projecting portion of the fin 40 and is of greater width than the fin and extends laterally beyond 15 each side thereof and overlaps the surface of the work table.

A knob or handle 44 is secured to, and up-stands from, the forwardly projecting portion of the fin 40 and provides means where- 20 by the form may be conveniently moved over the work table manually by the operator of the machine. The forward movement of the form is limited by a stop 45, which in the present instance is in the form of a U shaped 25 member secured to the front edge of the work table in registry with the slot 41 with its extremities projecting upwardly beyond the surface of the work table on each side of the slot and adapted to engage the end of the 30 base 43 of the spring finger 42.

At the forward limit of its movement the form is in its inoperative position in which it is located upon the forward extension of the table top and in advance of other parts of 35 the machine hereinafter referred to, so that it is readily accessible and may be conveniently loaded in any suitable manner, as for instance manually by the operator, with certain of the parts of the box, namely, the front side 40 and the bottom thereof. The side of the box is inserted between the front face of the form and the finger 42 and is held therebetween with its lower edge resting upon the upwardly facing shoulder 38. The bottom of the 45 box is thereupon applied in inverted position and placed upon the platform 30 with its front edge abutting against the upper portion of the finger 42, which thus serves to locate the bottom in proper position from front 50 to rear of the form with its front edge sub-stantially flush with the outer surface of the front side of the box. While the bottom thus extends over the front side of the box it is to be noted that it is supported in spaced 55 relation thereto in the normal position of the platform.

In order to expedite the assembling of the side and bottom on the form, I provide a pair 60 of transversely spaced gauges 46 suitably fixed on the work table to receive the form therebetween in its inoperative position. there is a space between the respective gauges and the adjacent ends of the form substan-tially equal to the thickness of the boards subse-65 quently forming the ends of the box. Along

their front edges these gauges are formed with in-turned lips 47 which engage the vertical edges of the front side of the box as it is inserted behind the finger 42 and locate it in proper position on the form with these 70 edges flush with the end faces thereof. These gauges also project upwardly above the plane of the platform 30 and abut against the adjacent edges of the bottom of the box to locate it in proper position transversely of the 75 machine. It will be noted that the gauges are out-turned and inclined laterally and upwardly along their upper edges, to provide wings 48, which coact with each other and also with the inclined upper extremity of 80 the finger 42 to guide the bottom as it is placed in position upon the platform. The rear edges of these gauges are preferably out-turned in divergent relation, as indicated at 49. It is also desirable to provide for 85 the lateral adjustment of the gauges relatively to each other to permit them to be set for different sizes of boxes. To this end one of the gauges is shown as secured to the work table by means of bolts 50 passing through 90 transverse slots 51 formed in the table top. Although it is not usually necessary, the other gauge may also be similarly mounted.

When the form has been loaded with the front side and the bottom of the box it is moved to the rearward limit of its movement, which is regulated by means of an adjustable stop 52 in the form of a screw threaded into the work table below the top thereof and adjacent the rear end of the slot 41 and forming an abutment for the rear end of the fin 40. The form is then located upon the central portion of the table top and in its operative position in which it is in registry with transverse magazines 53 and a rear magazine 54, the former being each adapted to contain a plurality of ends for the boxes to be manufactured while the latter is adapted to contain a plurality of boards for forming the rear side. These magazines are mounted on the 100 table top with the transverse magazines 53 ex-tending along the lateral extensions 22 there-of and the rear magazine 54 extending along the rearward extension 23.

The magazines may be of any suitable construction and in the present instance are of skeleton form and each comprises a pair of parallel guides 55 that are arranged in op-posed relation and are properly spaced apart to form the sides of the magazine and receive the boards therebetween. The guides are preferably secured to the table top by means of bolts 56 passing through longitudinal slots 57 extending lengthwise of the guides, the bolts of one guide of each pair also ex-tending through slots 57' formed in the table 110 top at right angles to the guides. This permits the guides to be adjusted both in the di-115 rection of their length and also toward and away from each other as may be required in 120 125 130

setting the machine for boxes of different sizes. At their inner or adjacent ends the forward guides of the transverse magazines 53 may be angularly disposed to provide 5 wings 55 projecting forwardly in slightly divergent relation on opposite sides of the path of the form 28. The bottom of each magazine consists of a plurality of strips or rails 58 which extend lengthwise thereof and 10 are spaced apart transversely between the guides 55. The rails of the two transverse magazines 53 are spaced apart at their inner or adjacent ends so that the box form 28 will just fit nicely therebetween. The rails 15 of the rear magazine 54 abut against the rear edge of the bed 37 of the form when the latter is in its operative position and are raised slightly above the plane of the rails of the transverse magazines 53 so as to be flush with 20 the upwardly facing shoulder 38 at the rear of the form.

Suitable automatic feeding means are provided to supply the boards one by one from the magazines. In the present instance, such 25 feeding means comprise a device for applying a constant ejecting force, and a releasing device controlling the action of such ejecting force to discharge one board from each magazine in each cycle of the machine. However, 30 the invention is not limited to feeding means of this type, and suitable feeding means of a type applying an intermittent ejecting force may be employed, if desired.

Each magazine is provided with means for 35 supporting the boards in vertical position therein and applying pressure substantially evenly thereto to force them toward, and eject them from, the inner end or mouth of the magazine. This may be accomplished, for 40 instance, by lazy tongs 59 mounted adjacent the outer end of the magazine, a follower 60 being pivotally connected to the knuckle at the inner ends of the tongs and being pressed against the outermost board in the magazine 45 through the action of a tension spring 61 connecting the tongs at their outer ends.

To retain the boards in these three magazines and release them therefrom, as desired, in the operation of the machine, I provide a 50 jaw 62, which is superposed upon the work table and mounted thereon to rock about an axis extending transversely of the machine and located in front of the transverse magazines 53. The jaw is preferably U-shaped and 55 has its ends mounted on aligning pivots 63 carried by brackets 64 secured to the table top on opposite sides of the path of movement of the box form 28. In its normal position the jaw extends rearwardly from its pivots in a 60 substantially horizontal plane with its side members or legs 65 overlying the mouths of the transverse magazines 53 and its central portion 66 overlying the mouth of the rear magazine 54. On its under face the jaw is 65 provided at suitable intervals along its legs

and central portion with teeth 67 which bite into the upper edges of the innermost boards in the respective magazines and retain the same therein against ejection. As thus held by the jaw the innermost boards in the respective magazines are so located that when the form 28 is in its operative position they are spaced apart from the adjacent faces thereof a distance equal to the thickness of one board. A plurality of recesses 68 are 70 preferably formed in the inner edge of the jaw between the teeth, for a purpose to be hereinafter mentioned. In order to adjust the jaw transversely of the machine in setting the latter for the manufacture of boxes of different sizes, one leg 65 may be formed separately from the rest of the jaw and fitted to an extension 69 of the central portion and suitably clamped thereto in the desired relative position, as by a bolt 70. One or both 75 brackets 64 are also adjustably secured to the table top by a slot and bolt connection 71. It is also possible conveniently to remove the jaw and substitute another jaw therefor.

The jaw 62 is operated by means of an arm 90 72 projecting rearwardly from the central portion thereof and connected by link 73 to a treadle 74, suitably fulcrumed at 75 in the lower portion of the stand 3 and having limited rocking movement between upper and lower stops 76 and 77, provided on the stand. The treadle is normally raised against the upper stop 76, and yieldingly held in such position by a tension spring 78. By depressing the treadle the jaw is swung upwardly 100 about its transverse axis, to disengage the teeth 67 from, and release, the innermost boards in the respective magazines 53 and 54. These innermost boards are thus fed from the magazines under the ejecting force of the lazy tongs 59 and springs 61, and automatically advanced a distance equal to the thickness of the respective boards, and are thereby brought directly into assembled position on the form 28 against the rear and end faces thereof respectively, the rear side of the box being supported upon the shoulder 39. As the innermost boards are ejected, the next succeeding boards are, of course, moved into position to be engaged by 105 the jaw when it returns to its normal or fully gripping position upon the release of the treadle.

It is to be noted that the arrangement of the jaw is such that the teeth 67 are first released from the innermost board in the rear magazine before they are disengaged from the innermost boards in the transverse magazines. In other words, the jaw first assumes, upon the initial downward movement of the 110 treadle, the partly releasing and partly gripping position illustrated in Figure 4, before it is raised, upon the further downward movement of the treadle, to the full releasing position illustrated in Figure 5. This is impor- 115 120 125 130

tant in that it causes the ends of the box to be fed to assembled position just after the assembling of the rear side of the box, whereby to insure the ends overlapping the rear side to form the usual butt joints at the corners of the box. Of course, there is no necessary pause or break in the upward swinging movement of the jaw and hence the assembling of the rear side and the ends of the box is practically simultaneous, and yet the proper sequence is effectively preserved. As the bottom of the box is normally supported by the platform 30 in slightly raised position, clearance is afforded so that the rear side and the ends of the box may be assembled beneath the bottom without interference. When thus assembled, the box is ready for nailing.

By virtue of the relation between the magazines and the box form 28 in the operative position of the latter, the boards fed from the magazines in each cycle of the machine are assembled directly on the form in position for nailing. This avoids the necessity for complicated assembling means and makes possible a simple assembling means consisting of merely the feeding means and the box form or other suitable means for supporting such box parts in position to be nailed. Nevertheless, the invention is not limited to this simplified form.

The nailing mechanism, and the driving mechanism therefor, are preferably arranged and supported as a unit on a carrier frame 79, which is mounted on the standards 2 above the stand 3 and the work table 5, and which may be shifted vertically on the standards and fixed at the desired elevation above the work table to suit the height of the box to be made. This is an important feature since it permits the capacity of the machine to be varied independently of the work table so that the latter may be at all times maintained at the height found most comfortable and convenient for the operator, and most conducive to efficient results. The nailing and driving mechanism may also be readily applied to, and removed from, the main frame of the machine, as occasion requires, in view of the fact that they may be handled as a unit.

In the present instance the carrier frame 79 comprises transversely spaced side bars 80 and upper, lower, and intermediate cross members 81, 82, and 83 respectively. Each side bar is provided with a plurality of projecting sleeves 84, slidable vertically on the standards 2. The standards are provided with racks 85 with which mesh pinions 86 fixed on a shaft 87 extending transversely between and journaled in the side bars 80. The shaft 87 has a gear 88 meshing with a relatively small reducing gear 89 provided on a shaft 90, which also extends transversely of, and is journaled in, the side bars 80, and which is provided with a crank handle 91 on one end thereof. By turning the crank handle the

carrier frame may be conveniently shifted to the desired elevation, in which position it is retained by ratchet 92 mounted on the shaft 90 and engaged by a pawl 93. The carrier frame is further held in adjusted position by fixing the sleeves 84 to the standards 2, as by an arrangement of keys 94, and set screws 95, similar to that hereinbefore above described in connection with the sleeves 8 of the work table brackets 6.

Projecting forwardly from the carrier frame 79 at each side thereof is a pair of vertically aligned bearings 96 which are preferably, although not necessarily, carried respectively by sleeves 84 at the corresponding side of the frame. Each pair of bearings receives and supports a guide rod 97 which is slidably mounted therein and has its sliding movement limited by a pair of collars 98 fixed on the guide rod above and below the upper bearing 96. A cross-head 99 is secured to, and carried by, the lower ends of the guide rods so as to be supported below and in spaced relation to the lower bearings 96 when the guide rods are at the lower limit of their movement. Above the lower bearings 96 and between the same and the lower collars 98 another cross-head 100 is slidably mounted on the guide rods. These cross-heads 99 and 100 form the rear sides of a chuck frame 101 and a hammer frame 102 respectively, such frames being preferably rectangular in order to permit the driving of nails simultaneously along all four edges of a box.

Referring to the chuck frame, a pair of arms 103 are carried by, and project forwardly and substantially horizontally from, the opposite ends of the cross-head 99 and are formed with slots 104 in which the ends of the front side 105 of the chuck frame are received and adjustably secured in position by means of clamp nuts 106. A bar 107 extends between the front and rear sides of the frame with its ends slidable in slots 108 extending lengthwise thereof, clamps 109 being provided for securing the ends of the bar in adjusted position. This bar and one of the arms 103 constitute the ends of the chuck frame 101. A suitable number of chucks 110 are provided at the desired intervals around this frame and are adjustably mounted thereon in any convenient manner, as by means of clamps 111. At the end of the frame formed by the bar 107 the clamps 111 engage brackets 112 secured to the bar 107 and adjustable in a slot 113 extending lengthwise thereof. At the other end and the sides of the chuck frame these clamps 111 extend into and are adapted to be fixed in adjusted position in, the slots 104 and 108 respectively.

The hammer frame 102 is substantially similar in construction to the chuck frame and comprises a pair of arms 114, projecting forwardly from the cross-head 100 and

formed with slots 115 in which the ends of the front side 116 of the frame are received and held in adjusted position by means of clamp nuts 117. The ends of the frame are 5 formed respectively by one of the arms 114 and a bar 118 extending between the front and rear sides of the frame with its ends slideable in slots 119 therein, and held in suitably adjusted position as by clamps 120. 10 The hammer 121 are located around the hammer frame and correspond in number and position with the chucks 110. At the end of the frame formed by the bar 118 the hammers are preferably supported by brackets 122 se- 15 cured to such bar and adjustable in a slot 123 extending lengthwise thereof. The other end of the frame and the front and rear sides thereof are provided with inwardly projecting slotted plates 124 in which the hammers 20 are supported, and at the same time have sufficient play to insure their maintaining positions in vertical alignment with the corresponding chucks.

By virtue of the foregoing arrangement, 25 the chuck and hammer frames may be conveniently adjusted along both dimensions thereof to suit the size of the box to be nailed, and to support the chucks and hammers so that they will occupy their proper positions 30 in relation to the parts of the box assembled on the form 28 for nailing. The recesses 68 in the jaw 62 afford clearance for the chucks and permit them to be located for driving the nails along the edges of the box bottom 35 without interfering with the operation of the jaw.

Suitable nail feeding mechanism is employed with the chucks and hammers, and is 40 preferably supported on the intermediate cross bar 83 of the carrier frame. In the present instance this mechanism is of well known construction and comprises oscillatory nail boxes or hoppers 125 pivoted at their forward ends in operative relation to inclined track plates 126 from which telescopic nail chutes 127 lead to the respective chucks. Picker bars 128 are mounted at the lower ends 45 of the track plates and have a reciprocatory movement thereacross, under the influence of picker cams 129 carried by the hammer frame 102, so as to control the discharge of the nails into the chutes and deliver them one at a time to the respective chucks.

When the nailing mechanism is at rest the 55 hammer frame 102 is supported in its raised or inoperative position with the hammers retracted in the chucks, and in this position the cross-head 100, forming part of the hammer frame, abuts against the lower collars 98 on the guide rods 97 so that the guide shafts are 60 lifted, and the chuck frame 101 carried thereby is supported in elevated position with the chucks spaced above the bottom of the box assembled on the yielding platform 30. In the 65 operation of the nailing mechanism the ham-

mer frame moves downwardly on the guide rods and its initial downward movement permits the guide rods to slide in their bearings to the downward limit of their movement, whereby to automatically lower the chuck frame and bring the chucks thereof against the bottom of the box. The continued downward movement of the hammer frame advances the hammers in the chucks to drive the nails, the hammers preferably projecting 70 slightly beyond the chucks in the lowermost position of the hammer frame, as illustrated in Figure 1. It is to be noted that the lowering of the chucks and also the action of the hammers, serve to depress the bottom of the 75 box and its supporting platform against the action of the springs 35, so that the bottom is held in contact with the upper edges of the sides and ends as the nails are driven, and is separately secured thereto through the simultaneous driving of the nails along all four edges of the bottom. Thus the parts of the 80 box are preliminarily secured together in assembled position, through the nailing operation.

After the nailing, the hammer frame moves 85 upwardly and returns to its normal or inoperative position. As it approaches the end of its upward movement, it lifts the guide rods and the chuck frame through the contact of 90 the cross-head 100 with the lower collars 98. The raising of the guide rods and chucks releases the downward pressure upon the box bottom, whereupon the springs 35 restore the 95 platform to its normal position and thus lift 100 the nailed box to the position shown in Figure 10 in which it is partly stripped from the form 28.

The driving mechanism for the hammer frame is preferably mounted on the upper 105 cross member 81 of the carrier frame 79 and comprises connecting rods 130 arranged at opposite sides of the machine and pivoted at their lower ends to the hammer frame and at their upper ends to cranks 131 provided at 110 the opposite ends of a transverse driving shaft 132. This shaft is adapted to be driven from an electric motor 133, by means of a suitable gear train such as a gear 134 on the shaft of the motor meshing with a relatively 115 large gear 135 fixed on a sleeve 136 freely rotatable on a transversely extending counter-shaft 137. The sleeve also has a relatively small gear 138 fixed thereon, which meshes with a relatively large gear 139 on 120 the driving shaft. A fly wheel 140 is preferably provided on the motor shaft.

There is also a suitable train of gears 141 for transmitting motion from the driving shaft to a transverse shaft 142, provided at 125 its ends with cranks 143 which are connected by links 144 to the nail boxes 125 so as to oscillate the same about their pivots when the machine is in operation. The gears 141 are preferably so arranged that the shaft 130

142 is driven at one half of the speed of the driving shaft 132.

In order to control the rotation of the driving shaft 132 a suitable clutch 145 is provided between the same and the gear 139. This clutch has a cam shoulder 146 which is adapted to be engaged by a dog 147 mounted on a pivot 148, so as to hold the clutch in inoperative position and cause the gear 139 to run freely on the driving shaft. A spring 149 connected to the dog swings it upwardly about its pivot and normally holds it in position for engagement with the shoulder. The clutch is released to rotate the driving shaft by swinging the dog downwardly out of the path of rotation of the shoulder 146. This may be accomplished by a pull rod 150 which passes upwardly through a fork 151 at the free end of the dog and is formed with a downwardly facing shoulder 152 that engages the dog when the latter is in its raised position and is yieldingly held in engagement therewith by means of a spring 153 connected to the rod and forcing it forwardly within the fork. At its lower end this rod is pivotally connected to one end of an elbow lever 154 fulcrumed on a side bar 80 of the carrier frame 79, the other end of the elbow lever being connected by link 155 to an arm 156 projecting from a clutch rod 157 arranged substantially vertically at one side of the machine. The clutch rod is supported by, and mounted to rock in, upper and lower bearing brackets 158 and 159, the upper bracket being secured to the carrier frame 79 and supporting the clutch rod intermediate of its ends while the lower bracket is secured to the lower portion of the stand 3 and has the lower end of the clutch rod mounted therein with a step bearing.

The arm 156 is provided with a sleeve or collar 160 mounted on the clutch rod 157 to turn therewith. The sleeve is preferably formed of companion sections arranged, respectively, above and below the upper bracket 158, and telescoping therethrough with each other, a set screw 161 serving to hold the sections together. By this means the arm 156 is retained at all times in operative relation to the elbow lever 154, while its sleeve 160 telescopes with, and is adapted to slide vertically along, the clutch rod 157 in the vertical adjustment of the carrier frame 79.

Fixed on the clutch rod, adjacent its lower end, is a collar 162 provided with an outstanding pin 163, received in a fork 164, which is movable with, and about the same axis as, the treadle lever 74. The arrangement is such that when the treadle lever is depressed to its position against the lower stop 77 it turns the clutch rod 157, through the fork 164 and pin 163, and rocks the arm 156 and the elbow lever 154. This causes the elbow lever 154 to draw the pull rod 150 downwardly, which in turn, through the engagement of its

shoulder 152 with the free end of the dog 147, swings the dog downwardly against the action of its spring 149 to clear the shoulder 146, thereby releasing the clutch 145 so that the driving shaft 132 is rotated by and with its gear 139, to operate the nailing mechanism. 70

It will thus be seen that the single treadle 74 controls the automatic feeding of the rear side and the ends of the box, the automatic assembling of the same in position for nailing, and the operation of the nailing mechanism. Furthermore, the downward movement of the treadle first moves the jaw 62 upwardly to fully releasing position, before disengaging the dog 147 from the clutch shoulder 146. To insure this the prongs of the fork 164 are spaced apart a greater distance than the diameter of the pin 163, to provide lost motion between the treadle and the clutch rod 157. Therefore the nailing mechanism is caused to operate just after the feeding mechanism, and their proper sequence is maintained, although one follows the other with such a short interval that the operations are practically simultaneous. 80

Should it be necessary to make an adjustment after the assembling of the parts the operator may pause in the downward movement of the treadle before throwing the clutch, through the lost motion connection, to cause the parts to be nailed. Or the operator may allow the treadle to return to its initial position, as the operation of the jaw 62 will not have the effect of releasing further box parts while a box is assembled on the form 28. 100 Thus should the operator either pause or release the treadle, the machine is arrested in its cycle between the assembling operation and the nailing operation, so that the operator may make any adjustment which might be necessary. When next the operator depresses the treadle so as to engage the clutch, the nailing operation is performed precisely as though the downward movement of the treadle had not been interrupted. The operation of the clutch may thus be selectively controlled. 105

The driving shaft 132 is provided with the usual knock off pin 165 which, as the shaft rotates, impinges against the pull rod 150 and forces the same rearwardly in the fork 151 against the action of the spring 153, to disengage the shoulder 152 of the pull rod from the dog 147. On being thus released the dog 147 is restored by the spring 149 to its normal position to engage the shoulder 146 and automatically throw the clutch to stop the machine when the driving shaft has completed one revolution. The pull rod 150 is moved upwardly when the treadle 74 is released, and re-engages the dog to set the clutch control mechanism for the next operation. 115 120 125

From the foregoing description the operation of my improved nailing machine will be obvious. Outlining it briefly, the operator 120

starts with the box form 28 in its inoperative position, and partly loads the form by assembling thereon the front side and the bottom of the box. The operator then moves the form rearwardly to its operative position 5 beneath the nailing mechanism, and depresses the treadle 74 against its lower stop 77. Upon this movement of the treadle the rear side and the ends of the box are automatically fed from their magazines 54 and 53 and assembled 10 on the form, and immediately thereafter the nailing mechanism is automatically operated to cause the chucks 110 to be lowered and the hammers 121 to drive nails through the box bottom and into the sides and ends 15 of the box respectively. After the nailing the hammers and chucks are moved upwardly away from the nailed box and the nailing mechanism restored to its inoperative position, at which time the operation of the machine is stopped. When the pressure of the 20 nailing mechanism is removed from the bottom of the box, the springs 35 lift it slightly, as shown in Figure 10, to partly strip the box from the form. The operator then moves the form forwardly to withdraw the box from beneath the nailing mechanism, in which position it can be readily removed from the form, the removal being facilitated by the partial 25 stripping above referred to. After the removal of the box the operator draws the form 28 slightly further forwardly to return it to its inoperative or loading position against the stop 45, this being necessary in view of the fact that the forward movement 30 of the form is restricted when the box is carried thereon, by the lips 47 which are adapted to abut against the ends of the box as shown in Figure 14. The form may thereupon be reloaded and the operation repeated.

40 The box thus produced is reversed or turned right side up and appears as illustrated in Figure 16. The nails driven through the bottom of the box into the sides and ends thereof, respectively, preliminarily secure the box parts together in assembled relation, so that the box may be handled as a unit until and during its subsequent completion by fastening the sides and ends together at the 45 corners of the box in any desired manner and by any suitable means. It will be noted that in the box shown its ends project upwardly above its sides, as is usual in cigar boxes, to receive a cover, this arrangement being produced with my machine through having the shoulders 38 and 39 on the form 28 raised above the plane of the upper surfaces of the rails 58 forming the bottoms of the transverse magazines 53.

50 In a modified form of the invention, the finger 42 is mounted on the fin 40 for slight play toward and away from the front face of the form 28. To this end the base 43' of the finger is formed with longitudinal slots 166 through 55 which pass screws 167 fastening the base to

the fin. The knob or handle 44' for moving the form is attached to the base of the finger. When the form is drawn forwardly to its inoperative or loading position, the finger 42 is automatically moved slightly forwardly with respect to the form to permit the front side of the box to be more readily inserted therebetween by the operator. Upon the application of force to the handle to move the form rearwardly, the finger is automatically moved toward the form and returned to its normal position relative thereto so as to hold the side of the box firmly thereagainst.

70 It is to be understood that various other changes may be made in the construction and arrangement of the parts without departing from the spirit of the invention as defined in the appended claims.

75 Having thus described my invention I claim and desire to protect by Letters Patent of the United States:

80 1. In a nailing machine, the combination 90 of means for assembling box parts in position for nailing, means under control of the operator for controlling the operation of said assembling means, nailing mechanism, and a lost motion connection between said controlling means and said nailing mechanism, for causing the operation of said nailing mechanism.

95 2. In a nailing machine, the combination 100 of a magazine for parts to be nailed, feeding means therefor, a treadle operatively connected to said feeding means, nailing mechanism, and a lost motion connection between said treadle and said nailing mechanism.

105 3. In a nailing machine, the combination 110 of means for assembling box parts, nailing mechanism, a treadle operatively connected to said assembling means, and means including a lost motion connection between said treadle and said nailing mechanism, for causing the nailing mechanism to operate after the assembling means, in each cycle of operation of the machine.

115 4. In a nailing machine, the combination 120 of nailing mechanism, driving mechanism therefor having a clutch, means for operating said clutch, means for assembling box parts in position for nailing, and means operated by the initial movement of the clutch operating means, for causing the operation of the assembling means before the operation of the clutch.

125 5. In a nailing machine, the combination 130 of means for assembling box parts in position for nailing, means controlling the operation of said assembling means, nailing mechanism, driving mechanism therefor having a clutch, and means for actuating said controlling means and for selectively actuating said clutch.

130 6. In a nailing machine, the combination of means for assembling box parts in position for nailing, means for controlling the opera-

tion of said assembling means, nailing mechanism, driving mechanism therefor having a clutch, and a lost motion connection between said clutch and said controlling means.

7. In a nailing machine, the combination of 5 a magazine for parts to be nailed, means for ejecting such parts from the magazine, means for releasing such parts one by one from the magazine, nailing mechanism, driving mechanism therefor having a clutch, and a lost motion connection between said clutch and said releasing means.

8. In a nailing machine, the combination of 15 a magazine for parts to be nailed, feeding means, means for supporting the parts in position for nailing, nailing mechanism, driving mechanism therefor having a clutch, means for controlling the operation of said feeding means, and an operative connection 20 between said operating means and said clutch.

9. The combination of a form having means for yieldingly supporting a part of a box in position thereon, and means for 25 assembling sides and ends of a box on the form below and in spaced relation to said part.

10. In a nailing machine, the combination of 30 a form having a movable platform for supporting the bottom of a box, means for assembling other parts of a box on said form in spaced relation to said bottom, means for nailing said bottom to said other parts respectively, and yielding means supporting 35 said platform to afford clearance during the operation of said assembling means and also to apply stripping force.

11. A box form comprising a body, a platform mounted on the body and movable relatively thereto, and adapted to support the bottom of a box in inverted position, means for yieldingly supporting the platform in spaced relation to the body, and means for supporting the sides and ends of a box on the 45 body beneath and in spaced relation to the bottom.

12. In a box nailing machine, the combination of 50 a form for supporting the sides and ends of a box in assembled position, means on said form for yieldingly supporting the bottom of the box in spaced relation to said sides and ends, and means for pressing said bottom against said yielding means into contact with and nailing it to said sides and ends.

55 13. In a box nailing machine, the combination of means for yieldingly supporting the bottom of a box, means for assembling parts of a box frame below and in spaced relation to said bottom, and means for depressing said bottom into contact with and nailing it to said parts.

14. In a box nailing machine, the combination of 60 means for yieldingly supporting the bottom of a box in substantially horizontal position, means for moving parts of a box

frame substantially horizontally to assembled position below and in spaced relation to said bottom, and means for depressing said bottom into contact with and nailing it to said parts.

70 15. In a nailing machine, the combination of means for yieldingly supporting the bottom of a box in inverted position, and means for moving other parts of a box in a direction parallel to the plane of the bottom, into assembled position beneath and in spaced relation to the bottom.

75 16. The combination of nailing mechanism, a rectangular form, means for assembling parts to be nailed on three sides of said form when the same is in operative relation to the nailing mechanism, means for supporting another part to be nailed on the remaining side of said form, and means mounting said form for movement into and out of operative relation to said nailing mechanism and to said assembling means, in a path substantially normal to the last-mentioned side of said form.

80 17. In a nailing machine, the combination of nailing mechanism, a form having a yielding platform for supporting a part to be nailed, means mounting said form for movement into and out of operative position beneath said nailing mechanism, and means for assembling another part to be nailed, on a side of said form and beneath the part supported on said platform, when the frame is in its operative position.

85 18. In a nailing machine, the combination of 90 means for supporting a board in a position to be nailed, means arranged in cooperative relation to said supporting means for holding a plurality of boards with the innermost board spaced from said supporting means a distance substantially equal to the thickness of a board, and registering with said supporting means in a direction normal to the plane of said innermost board, and means for feeding boards one at a time from said holding means directly into assembled position 95 on said supporting means.

100 19. In a nailing machine, the combination of 105 a magazine for parts to be nailed, feeding means therefor, a pivoted member having teeth for engaging the innermost part in said magazine, and means for rocking said member about its pivot to permit said parts to be fed from said magazine.

110 20. In a nailing machine, the combination of 115 a magazine adapted to hold a plurality of boards in substantially vertical positions with their faces in contact with each other, means for moving the boards in said magazine to eject them therefrom, a member extending over said magazine and provided with 120 teeth adapted to bite into the upper edge of the innermost board therein, and means for moving said member to permit the ejection of 125 a board.

130 21. In a nailing machine, the combination

of means for supporting a part in position to be nailed, a magazine for holding a plurality of said parts, means for feeding said parts from said magazine into position on said supporting means, a treadle for controlling the operation of said feeding means, nailing mechanism, and an operative connection between said nailing mechanism and said treadle.

22. In a nailing machine, the combination of means for supporting parts in position to be nailed, a plurality of magazines for holding a plurality of said parts, means for feeding parts from said magazines to assembled positions on said supporting means, a member adapted to engage the innermost parts in all of said magazines, and means for operating said member to permit parts to be fed substantially simultaneously from said magazines.

23. The combination of a form, a series of magazines for parts to be nailed, converging toward said form with their inner ends opposite the same in substantially the plane thereof, and means for feeding parts from said magazines to assembled positions upon said form and for timing said feeding to assemble a part from an intermediate magazine at a different interval from parts from other magazines.

24. In a nailing machine, the combination with a work table, of a main frame, a carrier frame mounted on said main frame above the work table, nailing mechanism supported by said carrier frame, driving means for said nailing mechanism also supported on said carrier frame, said carrier frame, nailing mechanism and driving means being movable as a unit relatively to said main frame and toward and away from said work table, and means for supporting said carrier frame at different elevations.

25. In a nailing machine, the combination with a work table, of a main frame, a carrier frame mounted on said main frame above the work table, nailing mechanism supported by said carrier frame, driving mechanism for said nailing mechanism also supported on said carrier frame and including a clutch, said carrier frame, and nailing and driving mechanisms being movable as a unit relatively to said main frame and said work table, means for supporting said carrier frame at different elevations, means mounted on said carrier frame for operating said clutch, means mounted on said main frame for actuating said clutch operating means, and means operatively connecting said last-mentioned means and said clutch operating means in the different positions of said carrier frame.

26. In a nailing machine, the combination of a magazine for parts to be nailed, feeding means therefor, nailing mechanism, driving mechanism having a clutch, and means for operating the clutch including a lost motion

connection, which last mentioned means is operatively connected to said feeding means.

27. In a nailing machine, the combination of means for supporting the sides and ends of a box in assembled position, means for yieldingly supporting another part of the box above and out of contact with said sides and ends and permitting it to be moved into contact therewith in the direction of yield, and means for depressing said last mentioned part against its yielding supporting means, into nailing position in contact with said sides and ends, and nailing it thereto to secure said parts together in assembled relation.

28. A box form comprising means for supporting the bottom of a box, means for supporting the sides and ends of the box in fixed position beneath and in spaced relation to the bottom, and means for yieldingly permitting the bottom of the box to move downwardly into contact with said sides and ends in the direction of yield.

29. In a nailing machine, the combination of means for supporting the bottom, sides and ends of a box in position for nailing, means for nailing the bottom to the sides and ends to form a preliminary assembly in which the sides and ends are unsecured to each other, and means for applying stripping force to move said preliminary assembly relatively to said supporting means.

In testimony whereof, I have signed my name to this specification.

CHARLES S. PRICE.
